UNITED STATES PATENT OFFICE.

THOMAS D. BOYLES, OF SCHENECTADY, NEW YORK, ASSIGNOR TO GENERAL ELECTRIC COMPANY, A CORPORATION OF NEW YORK.

SYNCHRONIZING APPARATUS FOR ALTERNATORS.

SPECIFICATION forming part of Letters Patent No. 717,331, dated December 30, 1902.

Application filed July 27, 1900. Serial No. 24,989. (No model.)

To all whom it may concern:

Be it known that I, THOMAS D. BOYLES, a citizen of the United States, residing at Schenectady, in the county of Schenectady and State of New York, have invented certain new and useful Improvements in Synchronizing Apparatus for Alternators, (Case D, No. 1,462,) of which the following is a specification.

10 In systems of electric distribution by alternating currents it is necessary in changing the number of generating units at the station to determine the exact moment of phase identity between a machine about to be cut in and those already connected with the distribution-circuit. It is customary for this purpose to employ as a phase-indicator an incandescent electric lamp which is so arranged that it may be connected in circuit 15 with the machine being cut in and with the distributing bus-bars or may be put in inductive relation with these sources, the lamp then indicating by its flashes the proximity of phase of the two sources. Sometimes a 20 voltmeter is employed as the phase-indicator and is a more accurate means of defining the instant when the phases coincide. Sometimes both phase-indicators are employed, a lamp or lamps being employed on the panel 25 of the switchboard corresponding to each machine and a voltmeter being located at some suitable part of the board within view of the operator when throwing in any machine. The voltmeter being an expensive instrument, 30 but a single one is employed for all the machines. To put the voltmeter in the same relation to the lamps of any machine requires considerable wiring unless the circuits be specially designed, and also requires a complication in the switch operation to produce 35 the necessary circuit relations to enable them to stand in the same relation to the sources of current being synchronized. My invention involves an organization of this character in which a simple system of wiring permits the voltmeter and lamps to be placed in 40 similar relation to the bus-bars and any machine.

In carrying out the invention I provide, in 45 addition to the synchronizing bus-bars, (which may or may not be the same as the distribut-

ing bus-bars,) an auxiliary conductor, with which one terminal of the several synchronizing-lamps and the voltmeter connect in parallel, the other terminal of the synchronizing devices connecting with one of the synchronizing bus-bars, the latter being adapted to be charged with electric potential by any machine.

My invention also involves switches for throwing into operative relation to any pair of machines the phase-indicating devices.

The several features involved in my invention will be more particularly hereinafter described and will be definitely indicated in the claims appended to the specification.

In the accompanying drawings, which illustrate my invention, Figure 1 is a diagram of a system embodying my improvements, and Figs. 2 and 3 are perspective views of plug-switches for coupling the phase-indicating devices into circuit.

1, 1^a, and 1^b represent a group of alternating-current dynamo-electric machines. 2 and 2^a represent the distributing bus-bars with which said machines may connect in parallel, and 3, 3^a, and 3^b represent controlling-switches for connecting the respective machines with the bus-bars. On the generator side of each switch is a step-down transformer 4 4^a 4^b, the low-potential winding of which is connected to socket-contacts 5 6 5^a 6^a, &c. These contacts form a part of a group of six contacts, as indicated at 5 6 7 8 9 10, 7 and 8 connecting with a pair of synchronizing bars 11 11^a, and 9 and 10 forming the terminals of a branch circuit, including one or more incandescent lamps 12. One of the lamp-terminals is connected by a conductor with a bar 13, this terminal of the several lamps being in parallel relation with said conductor. Between the conductor 13 and one of the synchronizing-bars, as 11^a, is connected a voltmeter 14. For connecting up the machine I provide a six-point plug and a four-point plug, as indicated in Figs. 2 and 3. The dotted lines between the plugs in these figures indicate cross-connections between the plug-contacts to which they lead. It will be observed that the four-point plug 100 is cross-connected and that when inserted in contacts 5, 6, 7, and 8, as indicated on the

machine at the extreme right of the diagram, it reverses the terminal with the transformer it connects with respect to the synchronizing bus-bars, thereby putting it in series relation with a transformer connected into circuit by the six-point plug. The latter plug is so arranged that the distance between the contacts 7 and 8 is greater than the distance between the contacts 7 and 9, this being desirable to prevent mistakes on the part of the operator in plugging in a transformer. The diagram Fig. 1 represents the machine 1 as being synchronized. The operator has put the four-point plug in the transformer-circuit of a machine already in the distribution-circuit—as, for example, 1^b—and the six-point plug in circuit with the transformer corresponding to machine 1. It will be seen that the voltmeter 14 and the lamps 12 are in parallel relation to each other and yet are both in series relation to the two machines 1 and 1^b. The circuit may be traced as follows: Starting from the lamps 12, we pass to the contact 10, thence across the plug to 5, through the secondary of transformer 4, across the plug from 6 to 8, to the synchronizing bus-bar 11, thence to the four-point plug of machine 1^b, through the secondary of transformer 4^b and back through the four-point plug to synchronizing-bar 11^a, thence to contact 7, and across the plug to contact 9, to the other terminal of the lamp 12. Thus the secondaries of the two transformers 4 and 4^b are in series relation with the lamps, and when there is phase identity, as indicated by a steady brilliancy of the lamp, the switch of the machine 3 may be thrown, coupling said machine in parallel relation with the distributing bus-bars 2 and 2^a. It will be noted that the voltmeter is in parallel with the lamps, the circuit being from the point 10 by way of conductor 13, voltmeter 14, synchronizing bus-bar 11^a, to contact-points 7 and 9. It will be observed, moreover, that the voltmeter stands in a similar relation to any machine of the bank which may be connected with the distributing bus-bars. It is therefore evident that a single voltmeter may be used to synchronize and may be employed simultaneously with the lamps, thus affording convenience and accuracy in connecting up the several machines with a simple arrangement of circuits symmetrically arranged and cheap to install.

Having thus described my invention, what I claim as new, and wish to secure by Letters Patent, is—

1. Means for synchronizing alternating-current dynamo-electric machines, comprising synchronizing bus-bars, a phase-indicator for each machine, means for imposing potentials

derived from sources to be synchronized in series relation to the phase-indicator of the machine being synchronized, and a voltmeter in parallel with any phase-indicator connected in circuit. 65

2. Means for synchronizing alternating-current dynamo-electric machines comprising a synchronizing-circuit, a phase-indicator for each machine, switches for imposing potentials derived from several machines one of which is to be synchronized in series relation to said circuit, and a voltmeter in said circuit common to all machines in the same relation thereto irrespective of the particular machine being synchronized. 70 75

3. Means for synchronizing alternating-current dynamo-electric machines comprising a synchronizing-circuit, transformers for imposing potentials derived from several machines on said circuit, a phase-indicator for each machine, and a voltmeter common to all machines connected across said circuit through a conductor in parallel relation to the several transformers. 80 85

4. Means for synchronizing alternating-current dynamo-electric machines comprising a synchronizing-circuit, potential-transformers from the several machines in parallel relation to said circuit, a phase-indicator for each machine, a synchronizing-voltmeter common to all machines connected across said circuit through a conductor connected in parallel with the several transformers, and switches for coupling any pair of transformers in the synchronizing-circuit. 90 95

5. Means for synchronizing alternating-current dynamo-electric machines comprising a plurality of transformers corresponding to the several machines, switches for connecting any pair of transformers in circuit, synchronizing-lamps corresponding to the several machines in circuit with said transformers, and a voltmeter in shunt to any lamp when connected. 100 105

6. Means for synchronizing alternating-current dynamo-electric machines comprising transformers corresponding to the several machines, a synchronizing-circuit, switches for connecting two transformers in series in said circuit, an auxiliary synchronizing-conductor, an incandescent lamp in series with the transformer of the machine being synchronized, and a voltmeter in shunt to the lamp through said auxiliary conductor. 110 115

In witness whereof I have hereunto set my hand this 24th day of July, 1900.

THOMAS D. BOYLES.
